UNITED STATES PATENT OFFICE.

ALBERT R. W. GOTTSCHALK, OF OTTAWA, KANSAS.

REFRIGERATOR.

SPECIFICATION forming part of Letters Patent No. 341,472, dated May 11, 1886.

Application filed November 21, 1885. Serial No. 183,507. (No model.)

To all whom it may concern:

Be it known that I, ALBERT R. W. GOTTSCHALK, a citizen of the United States, residing at Ottawa, in the county of Franklin and State of Kansas, have invented certain new and useful Improvements in Refrigerators; and I do hereby declare that the following is a full, clear, and exact description of the same, reference being had to the annexed drawings, 5 making a part of this specification, and to the letters and figures of reference marked thereon.

Figure 1 is a sectional view of a refrigerator embodying my invention; Fig. 2, a detail view, in perspective and on an enlarged scale, of the 15 ice-pan, and Fig. 3 a transverse section thereof.

The present invention has relation to certain new and useful improvements in refrigerators and in the ice-pans therefor; and the object thereof is to improve their construction, where- 20 by a circulation of pure cold dry air with the least possible ventilation from outside re- sources, is secured, or, in other words, to guard as much as practicable against the outer air and moisture, whereby any article of food 25 will be preserved in such a manner as to prevent its decomposing; also, to prevent the most susceptible substance from being contaminated by the odor, be it good or bad, of any other article within the refrigerator and 30 without wasting the ice.

A further object of the invention is to provide means whereby the action of the warmer air passing around the ice and displacing the colder air, creates by the current thus estab- 35 lished sufficient ventilation that will in conse- quence expel such warm air and foul gases arising from the food placed on the shelves; also, constructing the ice-pan in such manner as to prevent any accumulation of moisture or 40 condensation underneath, which otherwise would be produced by the contact of warmer air entering the colder atmosphere, thereby rendering the refrigerator absolutely free from dampness, and the air kept at all times dry and 45 pure. These several objects I attain by the construction substantially as shown in the drawings, and hereinafter described and claimed.

In the accompanying drawings, A represents the preserving-chamber of the refrigerator 50 with any suitable arrangement of slatted shelves. In the present instance I have shown three shelves; a b c, the two upper ones extend-

ing only to the vertical partition d and resting on cleats e, secured to the side of the preserving-chamber and to the partition; the lower shelf, e, extending the entire width of the chamber, and also supported on cleats f. An outer casing, B, surrounds the walls of the preserving-chamber A in such manner as to leave an air-space, g, between the walls and casing, 60 which extends entirely around the four walls, as shown in Fig. 1.

The partition d divides a part of the chamber A into a compartment, C, for the ice, said compartment having suitable cleats, h, for sup- 65 porting thereon an ice-pan. This ice-pan is of peculiar construction, consisting of a double incline bottom, D, the incline sides joining a central drip-channel, i, which communicates with the upper end of a discharge-pipe, E, ex- 70 tending down through the lower wall of the chamber A and through the bottom of the casing B, and terminates in a trap, l. Immediately under the double incline bottom D, and extending the entire area of its surface, is an 75 air-tight chamber, F, and the bottom has above it a confining-rim, G, to retain the ice in the pan. This rim G is held some distance above the bottom D of the pan by means of supports k, and the rim has an inwardly-inclined flange, 80 m, to receive the drippings from the ice and conduct them onto the bottom, from whence it passes into the drip-channel i into and down the pipe E, always leaving a sufficient amount of water in the trap l to prevent the entrance 85 of air. The pan is provided with the usual grating for supporting the ice, and the pan is removable from the compartment C, when desired, for cleaning or other purposes, the pipe E being detachable therefrom. The air-tight 90 chamber F is to prevent the adhesion or gathering of any moisture or condensation on the bottom of the pan, which without such chamber would naturally occur when, by opening the doors of the refrigerator, the entering warm 95 outer air would come in contact with a colder surface. By the employment of the air-tight chamber the bottom of the pan is always kept dry and free from moisture. The inner side of the casing B is preferably lined with "refrigerator paper felt," which is a non-conducting material, thus lessening considerably the 100 consumption of ice. The chamber A and casing B are held a proper distance apart to form

the air-space *g* by means of the stays *n*, which are perforated to allow of an easy and free circulation of air through the space and around the preserving-chamber. The warm air coming in contact with the ice and getting cooler will pass over the ice-pan through the preserving-chamber *A* downward, and gravitate toward the bottom of the chamber, as indicated by the arrows, and thence enter through aperture *p* into the surrounding space *g*, after which it rises and enters again the preserving-chamber through the apertures *r*, and again be attracted by the ice through the perforation or aperture *s* in the partition *d*, and in the side 15 wall of the chamber into the compartment *C*, and so on, creating a continuous rotary motion of the air, and thereby cooling and purifying the atmosphere of the provision-chamber, and at the same time expelling the warmer air and 20 foul gases through the aperture *t* in the casing *B*.

Having now fully described my invention, what I claim as new, and desire to secure by Letters Patent, is—

25 1. The combination, with a refrigerator, of an ice-pan provided with a closed air-chamber, a double inclined bottom having a drip-chan-

nel, and a confining-rim provided with an inwardly-inclined flange around its four sides, said rim being supported above the bottom of 30 the pan to leave a space for the passage of the circulating air, substantially as and for the purpose set forth.

2. The combination of a refrigerator provided with an air-space around its four sides, 35 apertures for the passage of the circulating air into the preserving-chamber and for the escape of the warm air and foul gases, suitable provision-shelves and ice-compartment, and an ice-pan having a closed air-chamber, a double 40 inclined bottom formed with a drip-channel, a flanged rim supported above the bottom, and a discharge-pipe communicating with the drip-channel, extending down through the bottom of the refrigerator and provided at its end with 45 a trap, substantially as and for the purpose specified.

In testimony that I claim the above I have hereunto subscribed my name in the presence of two witnesses.

ALBERT R. W. GOTTSCHALK.
